UNITED STATES PATENT OFFICE.

ALEXANDER F. WINTERS AND BASIL R. CRAMPTON, OF GRAND RAPIDS, MICHIGAN.

LATCH.

Application filed April 27, 1923. Serial No. 634,951.

To all whom it may concern:

Be it known that we, ALEXANDER F. WINTERS and BASIL R. CRAMPTON, citizens of the United States of America, residing at Grand 5 Rapids, in the county of Kent and State of Michigan, have invented certain new and useful Improvements in Latches; and we do hereby declare the following to be a full, clear, and exact description of the invention, such as will enable others skilled in the art to which it appertains to make and use the same.

The present invention relates to a latch construction used on doors of articles of 15 furniture, such as refrigerators, cabinets and the like having swinging or hingedly mounted doors. This latch, in conjunction with a suitable strike or keeper mounted on the door jamb or casing serves to hold the 20 door in closed position.

It is a primary object and purpose of the invention to make a latch which through spring action serves to automatically hold the door in closed position and has a tendency to wedge the door tightly shut, this being of especial value in latches for refrigerator doors wherein escape of the cold air from inside the refrigerator is to be obviated as much as possible. A further object of 30 the invention is to provide the latch with mechanisms whereby when the same is operated to unlatch and open the door to which it is attached, the latch lever is automatically freed from the influence of the spring 35 acting thereon, and when the door is closed, the latch lever may pass over the strike or keeper freely without imparting any strain whatever to the screws by means of which the latch is attached to the door, or 40 to the hinges which mount the door; and immediately after the latch lever has passed the keeper, the spring is automatically released to act on the latch lever and press it into latching and wedging position with respect to the keeper. A still further object 45 of the invention is to provide a latch structure which is so constructed that the variations which take place in the door in swelling or shrinking, or in the variations which 50 may take place in manufacturing the door so as to have its dimensions slightly greater or less than the exact dimensions, have no effect on the working of the latch as an effective door holding closure, this being a feature of great practical value. These objects and purposes, together with many

others not at this time specifically enumerated, will appear as understanding of the invention is had from the following description, taken in connection with the accompanying drawings, in which,

Fig. 1 is a front elevation of the latch and keeper therefor shown mounted on a door and door casing which are shown fragmentarily.

Fig. 2 is an under plan view of the latch and keeper, the door and its casing being in horizontal section.

Fig. 3 is a side elevation of the keeper and latch, the door casing appearing in 70 vertical section.

Fig. 4 is a view similar to that shown in Fig. 1, with the upper side of the latch casing cut away to show the interior mechanism of the latch.

Fig. 5 is a horizontal section through the latch at a point just below the spring holding and trigger release member which is shown in elevation and in the position which it occupies when the spring is automatically 80 held from action on the latch lever.

Fig. 6 is a rear elevation of the complete latch assembly.

Figs. 7 to 13 are perspective views of the 85 separate elements used in making up the latch assembly.

Fig. 14 is a transverse section through a somewhat modified form of latch structure.

Fig. 15 is an under plan view thereof.

Figs. 16 to 19 inclusive are perspective 90 views of the modified forms of elements entering into the modified form of latch structure.

Like reference characters refer to like parts in the several figures of the drawings.

The door 1 to which the latch is to be attached may be of any conventional construction, and adapted to be hingedly mounted so as to close a door opening bounded by the door casing 2. Only a fragmentary portion of the door and its casing is shown, being those parts where the latch and its keeper are mounted; the latch at the free vertical edge of the door, and the keeper at the vertical side of the casing opposite 105 that at which the door is hinged.

The keeper includes a base 3 which is secured by screws 4 to the door casing 2. From this base, integral therewith and projecting outwardly is a post 5 which is bent 110 upwardly at an angle to the vertical for a distance and which terminates in a down-

wardly and outwardly extending lip 6, the upper side of which has a cam formation as indicated at 7. The inner side of the upwardly bent portion of the post 5 has an 5 inclined cam surface, as indicated at 8. At one side of the post 5 an outwardly extending ledge 9 is integrally formed, as best shown in Figs. 1 and 2, the same extending toward the door 1.

10 The latch proper includes a casing or housing 10 formed with upper and lower extensions 11 through which screws 12 are passed into the door for securing the said casing or housing and the mechanism mounted therein to the door. The detailed elements of the latch are shown separately in Figs. 7 to 13 and will now be briefly outlined as to each.

15 The casing or housing is formed from a single piece of relatively heavy sheet metal to form the raised housing portion 10 and the oppositely projecting lower extensions 11. In opposite sides of the housing portion 10 openings 13 and 15 are made by cutting 20 away the material and near the inner edge of the side where the opening 13 is made slots 14 are cut as shown. In a similar manner the slots 16 are cut near the inner edge of the side in which the opening 15 is made. 25 A tongue 17 projects inwardly from the upper side of the housing 10 into the opening at 15, being separated by a slot 18 from the adjacent metal of the housing.

30 A base 19 formed from a single plate of sheet metal is used to fill the bottom of the housing having portions cut away and openings made therethrough to pass the screws 12 in the attachment of the latch to the door. At one side, a narrowed portion 20 extends outwardly for a short distance, is then narrowed still more, as indicated at 21 and terminates in a wider portion from which the tongues 22 extend, as shown in Fig. 8, said tongues being adapted to be seated in the slots 14 of the housing in the 35 assembled structure. A relatively wide and short tongue 23 extends from the opposite side of the base plate 19, its side edges being adapted to be received in the slots 16. 40 Two tongues 24, with a slot 25 between them having a width equal to the width of the slot 18, are turned upwardly from the edge 23 of the base and so positioned that when the base is attached to the housing, the slots 45 18 and 25 are in direct alinement. Substantially at one corner of the base, a wide tongue 26 is struck therefrom and bent upwardly for a distance and then bent over in substantial parallelism with the base, as 50 at 27. Alined openings 28 are made in the overhanging portion 27 and the base, as shown in Fig. 10.

55 An elongated latch lever 30 made as an integral casting is used, one end being formed into a handle 31 and the other into

a head 32 formed at one side with an inclined cam side 33. An opening 34 is made through the handle between its ends and near said opening, a lug 35 is formed to project to one side of the handle, a concaved 70 groove 36 being made in one side of the lug.

The latch lever is adapted to be pivotally mounted on the base, passing between the same and the overhanging portion 27 of tongue 26 with the opening 34 alined with 75 the openings 28. A headed pin 37 is passed through the alined openings to make the pivotal connection. Such pin does not need to be headed or riveted over after passing through the openings as in the assembly, the 80 head of the pin comes immediately below the upper or outer side of the housing 10 which holds it from displacement.

85 A spring carrying bar 38, formed from a single piece of flat metal, is provided at one end with a head 39, rounded at edge to seat in the recess 36 of lug 35. The bar is widened where it joins the head 39 but is not as wide as the head is long so that lower and upper shoulders 40 and 41 are made as 90 shown in Fig. 13. The opposite end of the bar is widened for a portion of its length, there being a catch shoulder 42 on the inner under side of the bar at the juncture of the narrower and wider portions of the bar. A 95 coiled spring 43 is placed over the bar, one end of which seats against the lower shoulder 40. The bar 38 is hardened so as to be able to withstand hard service to which it 100 is subjected.

105 The final element of the latch construction is a member 44, shown in Fig. 11, made from flat metal and provided with an elongated slot 45 therein, and at its inner side with a projecting lug 46. This member is 110 also of hardened material for the same reason that bar 38 is hardened.

115 In assembling the latch construction, the latch lever is pivotally connected to the base plate, as heretofore described; the member 44 is located against the tongues 24 with the lug 46 extending downwardly into the slot or notch at the end of slot 25, the spring 43 is placed over the bar 38 and the end of the bar is passed through the slot 45 in member 120 44 and the spring compressed so that the head 39 may be forced into the groove 36 of member 35. It will be noted that the edge of the head 39 is located at an angle to the bottom of the groove 36 (see Fig. 5), and that 125 there is a tendency for the force of the spring 43 to move the projecting end of bar 38 downwardly so that when the bar is moved outwardly so that the latching shoulder at 42 passes by the slot 45 in member 44 said shoulder moves into position to engage with the member 44 at the end of the slot 45, thereby holding the bar from return movement under the influence of the compressed 130 spring. After the parts of the latch are as-

sembled on the plate 19, the same is attached to the latch housing by passing tongues 22 through the slots 14 until the plate 19 may be received in the lower side of the housing, 5 and then moving the plate back so that the ends of the projecting part 23 may enter the notches 16. In making the base plate, a tongue 29 is formed at one side of the part 20 and is bent at an angle to the plane of the plate, as shown in Fig. 8, so that when 10 the plate is assembled with the housing, said tongue projects at an angle, as indicated in dotted lines in Fig. 5. This tongue 29 is bent back into the plane of the base, its end 15 coming within the side flange of the housing, thereby locking the plate with its attached latch elements thereon securely in place in the housing. The latch lever passes through the openings 13 and 15, the handle 31 ex- 20 tending to one side of the housing, and the head 32 to the opposite side.

When this latch is attached to the door 1 in the position shown in Fig. 1, and in Fig. 4, on pulling downward on the handle 31 of 25 the lever from the position shown in Fig. 1 to that shown in Fig. 4, the bar 38 is moved outwardly lengthwise and spring 43 compressed. The shoulder at 42 on bar 38 catches over the member 44 at the inner end 30 of slot 45, thereby freeing the lever from the action of the spring, and due to the overbalance of the weight of the handle 31, the lever remains in the position shown in Fig. 4. In such position the head 32 clears the 35 keeper and the door may be readily opened. On closing the door, the head 32 passes over the upper end of the keeper and the projecting end of the bar 38 then comes against the 40 ledge 9, disengaging the shoulder 42 from member 44 and bringing the spring again into action with the result that the lever 30 is moved to the position shown in Figs. 1 and 3, and the inclined side 33 of the head 32 of the latch lever rides against the inner 45 inclined side 8 of the keeper with a resultant wedging action which causes the door to shut tightly. If the bar 38 should not be held by the member 44, then the end 32 of the lever can ride over the cam 7 until it 50 passes to behind the keeper, but such action of the latch is not contemplated as the normal working of the latch and the cam 7 is used only as an insurance should there be an occasional failure of the bar 38 to latch with the member 44.

This latch is simple in structure, readily manufactured at low cost and is particularly effective in operation. Due to the fact that the spring is out of action when the door is 55 being closed, there is no strain imparted to the screws 12 which hold the latch casing or housing to the door, nor is there strain on the door hinges as is the case in latches of somewhat similar structure but in which the 60 end of the lever has to ride over a cam like

that at 7 and compress the spring every time the door is closed. This is a very important feature of the present invention. In addition, the structure permits tolerances sufficient that exact sizes and dimensions of the door may be varied slightly without detriment to the latch action. The door may swell in any direction or likewise shrink or sag to the extent of at least an eighth of an 70 inch, or the inner sides of the door may be dressed to this extent, the strike having the ledge 9 sufficiently broad and the hook of the keeper of sufficiently large size and with cam 8 long enough and of sufficient inclination to 75 compensate for the variations, the slot 45 in member 44 being considerably longer than the widest part of the outer end of bar 38 so that such changes in size are permitted 80 in the door without detriment.

In Figs. 14 to 19 inclusive, a somewhat modified form of construction is illustrated, and one which for assembly reasons may be preferred, being easier to assemble but working on identical principles of operation with that shown in the previously described figures of the drawing. In this modified form, the casing 10 is constructed the same as before except that in the openings 13 and 15 in opposite sides of the casing, inwardly extending tongues 47 are left, as shown in Fig. 16. These tongues lie in direct opposition to each other and in the casing between the same a bar 48 of flat metal is located, at one end having a part 49 turned substantially at right angles, in the end of which a notch 50 is cut of a width the same as the width of the tongues 47. The other end of the bar is likewise turned in the arc of a circle, as shown at 51 and is notched at 52 in a like manner. This bar is located between the 95 tongues 47 which are bent inwardly to seat in the notches 50 and 52 and clenched so as to securely connect the bar 48 to the housing. Prior to such connection a pin 37^a is secured 100 at one end to the bar so as to depend therefrom when the bar is attached in place in the housing, and the lever 30 may be mounted on this pin in the same manner that it is mounted on the pin 37 in the previously described structure, the pin passing through 105 the opening 34 in the lever.

The lever 30 and the bar 38 associated therewith are not changed in construction in any respect. The base plate 19^a in the modified form is changed, it comprising a substantially rectangular plate of metal, as shown in Fig. 19, from opposed edges of which projections 20^a and 23^a extend of a width equal to the width of the openings 13 and 15. A tongue 24^a is turned substantially at right angles from the plate at one side thereof corresponding to the position of the tongues 24 on the first base plate 19, and this tongue 24^a is notched at its end, as at 25^a, 120 the notch aligning with the slot 18 between 125 130

tongue 17 and the adjacent side portion of the casing when the base plate is attached in place. An opening 28^a in the plate 19^a is made for the passage of the pin 37^a therethrough 5 and the plate is depressed around said opening, making an embossing 53 as shown. The free end of the pin 37^a is milled on opposite sides, making slots 54 and when the plate 19^a is placed in position and the pin 10 passed through the opening 28^a the slots 54 are positioned at the outer side of the embossing 53 in position that the retaining clip 55 of U-shape may be entered in the slots, as shown in Fig. 15, binding and securing the 15 parts together.

With this construction, the action of the latch is the same as in the previously described construction. The plate 19^a, as a whole is case hardened and the member 44 20 may be eliminated, the shoulder 42 on the bar 38 engaging over the tongue 24^a when in its latching position. The assembly of the parts is simple. Various other modifications may be resorted to without departing from 25 the invention defined in the appended claims, and all such departures coming within the scope of the claims are to be considered as comprehended by the invention.

We claim:

- 30 1. A latch comprising a housing, a latch lever pivotally mounted therein, spring means to act on the lever to normally hold it in one position, and releasable latching means for holding the spring means out of operative relation to the lever whereby the lever is free for pivotal movement.
- 35 2. A latch comprising a housing, a latch lever pivotally mounted in and extending through the housing, a spring to act on the lever and normally yieldingly hold it in one position, a latch bar associated with the spring, and means with which said latch bar has releasable engagement for holding the latch bar in one position, said bar in said 40 position acting on the spring to operate the same out of operative relation with respect to the latch lever.
- 45 3. A latch comprising a support, a latch lever pivotally mounted thereon, spring means normally acting on the lever to move it in one direction, a bar around which the spring is placed, said bar at one end bearing against the lever to transmit the force of the spring means to the lever, said bar having a shoulder at one side, and a member over which the bar passes on operation of the lever and compression of the spring, said shoulder on the bar engaging against said member to hold the spring in compressed 50 form and out of operative association with the lever until the bar has been moved to disengage from the member.
- 55 4. A latch comprising a housing, a base plate attached to the housing at its open inner side, a latch lever pivotally mounted

on the plate and passing through the housing, said lever having a laterally extending lug between its ends, a bar having a head at one end to engage against the lug, a spring around the bar between the head and a side 70 of the housing, said bar extending outwardly beyond the side of the housing and having a shoulder on its inner side, and means over which the shoulder on the bar rides and with which it engages on operation of the latch lever in one direction thereby holding the spring from acting on the lever until the bar is released.

5. In combination, a door, a door casing, a keeper mounted on the casing, a latch on the door including a latch lever for engaging behind the keeper to hold the door in closed position, spring means acting on the latch lever for forcing the same into engagement with the keeper, means for rendering said spring means ineffective to act on the latch lever on manual operation of the latch lever to disengage it from the keeper, and means for automatically releasing the spring means on closing the door and after the latch lever has passed by the keeper to position to engage therewith.

6. In combination, a door, a door casing, a keeper mounted on the casing, a latch lever pivotally mounted on the door for engagement with the keeper when the door is closed to hold the door closed, spring means normally acting on the lever to force the same into engagement with the keeper, means for rendering said spring means ineffective to act on the latch lever on manual operation of the latch lever to disengage it from the keeper, said last mentioned means including a bar extending over the edge of the door to strike against the keeper on closing the door whereby the spring means is released to act on the latch lever after it has passed by the keeper to position to engage therewith.

7. In combination, a door, a door casing, a keeper mounted on the casing, a latch lever pivotally mounted on the door for engagement with the keeper when the door is in closed position, a spring acting on the lever to hold it in engagement with the keeper, means for automatically rendering said spring ineffective to act on the latch lever on operation of the lever to disengage it from the keeper, and means for tripping said last mentioned means on bringing the door to closed position, substantially as described.

8. In combination, a door, a door casing, a keeper on the casing, a latch lever pivotally mounted on the door to engage with the keeper to hold the door closed, a lug extending from the latch lever, a bar having one end to bear against the lug, said bar extending outwardly over the edge of the door, a spring on the bar tending to

hold the lever in engagement with the keeper, means with which the bar connects on manual operation of the lever to disengage it from the keeper to hold the spring from acting on the lever, and a ledge on the keeper against which said bar strikes on closing the door to move the bar to disconnect from said holding means and release the spring.

10 9. A latch comprising a housing having an open inner side, a base plate attached to the casing or housing and closing said inner side of the same, said base plate at one side having two spaced apart outwardly extending tongues turned at right angles to the base, and said housing having portions cut away at each side to provide openings, a latch lever pivotally mounted between its ends on the plate and passing through the 15 side openings in the housing, a laterally extending lug on the lever, a member formed with a slot therein mounted on the base plate and located against said tongues, a bar formed with a head at one end to bear 20 against said lug on the latch lever and passing through the slot in said member, said bar being formed on its inner side with a shoulder, a spring located around the bar between said member and head of the bar 25 and bearing at one end coil against the inner end of the head on the bar so as to normally impel the free end of the bar to move inwardly to engage the shoulder on the bar 30

with said member through which it passes when the bar is moved outwardly to carry 35 the shoulder beyond said member.

10. A latch comprising a housing, a latch lever pivotally mounted between its ends in the housing and extending through the same, a lug projecting from the lever to one side thereof, a bar formed with a head positioned at an obtuse angle to the length of the bar, said head being designed to seat against the lug, a guide member through which the bar passes, and a spring located around the bar between the head thereof and said guide member, said bar being formed on its inner side with a shoulder to engage with the guide member when the spring is compressed and the bar moved outwardly a predetermined distance, substantially as described.

11. In combination, a door, a latch on the door, a door casing, a keeper on the casing with which the latch engages when the door is closed, spring means acting on the latch to normally hold it in engagement with the keeper, and means to releasably hold said spring means from acting on the latch when the door is opened, said means being automatically released by striking the keeper on closing the door, substantially as described.

In testimony whereof we affix our signatures.

ALEXANDER F. WINTERS.
BASIL R. CRAMPTON.
